UNITED STATES PATENT OFFICE.

EUGENE L. TINKHAM, OF HOPEDALE, MASSACHUSETTS, ASSIGNOR TO DRAPER CORPORATION, OF HOPEDALE, MASSACHUSETTS, A CORPORATION OF MAINE.

WARP STOP-MOTION FOR LOOMS.

1,385,734.

Specification of Letters Patent. Patented July 26, 1921.

Application filed January 15, 1921. Serial No. 437,581.

To all whom it may concern:

Be it known that I, EUGENE L. TINKHAM, a citizen of the United States, and residing at Hopedale, in the county of Worcester and State of Massachusetts, have invented an Improvement in Warp Stop-Motions for Looms, of which the following description, in connection with the accompanying drawings, is a specification, like characters on the drawings representing like parts.

This invention relates to warp stop motions whereby when a warp thread breaks or becomes too slack, loom stoppage is effected.

When a warp thread breaks or becomes too slack for the production of perfect cloth, it is desirable that the loom be stopped to enable the loom attendant to correct the fault either by piecing the broken warp thread or correcting its slack condition. Various types of warp stop motions have heretofore been devised, but much time is lost and inconvenience experienced by the loom attendant in finding the faulty warp thread. The drop wires are usually arranged in rows very close together, and when a warp thread breaks or becomes too slack, the drop wire controlled by that warp thread will drop, and in the constructions heretofore devised, will effect loom stoppage. When the attendant seeks to locate the defective warp thread there is nothing to indicate its position, and in some cases means independent of the warp stop motion, have been proposed for enabling the loom attendant to locate the fallen drop wire. Such means, however, add to the complication of the loom mechanism, and is not always satisfactory.

One of the objects of the present invention is to provide a warp stop motion which in itself and by reason of the fallen drop wire, shall self-indicate the position of the broken or slack warp thread. An important feature of the present invention, therefore, consists in a plurality of drop wires arranged in two rows and a detector which is positioned between adjacent rows of drop wires, the drop wires of each row and the

detector being so constructed and arranged that when a drop wire of either row fails to be supported by its warp thread, it will embrace or straddle a portion of the detector and be bent by the detector before the latter is stopped, to thereby separate the drop wires of the row in which the fallen drop wire is located. Thus the loom attendant's attention is at once directed to the location of the defective or broken warp thread.

Another object of the invention is to provide a warp stop motion of simple construction which will be effective not only to stop the loom, but to locate the defective warp thread.

The above and other features of the invention will be described in connection with the accompanying drawings which show one good, practical form of the invention, wherein:

Figure 1 is a perspective view of a sufficient portion of a warp stop motion to make clear the construction and mode of operation of the present invention, some of the parts being omitted or broken away for clearness of illustration;

Fig. 2 is a detached perspective view of a portion of a warp stop motion showing the condition of parts when a drop wire fails to be supported by its warp thread; and

Fig. 3 is a rear elevation of a portion of the warp stop motion showing the separated relation of the drop wires of a row wherein one of the drop wires has been released by its warp thread.

In the present invention the drop wires are arranged in rows and the detector is positioned between the adjacent rows of drop wires. The detector and drop wire guides may be supported upon a bracket secured to the sides of the loom frame, and a train of mechanism is associated with the detector for giving the detector its detecting movement and to effect loom stoppage when the detecting movement is arrested by a released drop wire. Many forms of mechanism for effecting stoppage of the loom upon the breaking of a warp thread

2
are now well known and illustration of the details of such mechanism has not herein been made, since they are well understood and do not form part of the present invention.

In the drawings: 1 represents a lug or projecting bracket extending from one side of the loom frame, it being understood that a similar construction is provided at the 10 opposite side of the loom. Adjustably mounted upon the projecting bracket 1 is the support 2 which may be conveniently adjusted with respect to the bracket by the bolt 3 and slot 4. The support 2 carries the 15 side member 5 of the warp stop motion which consists of a plate which may be integral with or secured to the support 2, one of such plates being at each side of the loom.

20 Mounted in suitable bearings at the top of the side plates 5 are the rods 6 which extend transversely of the loom and are clamped in place by set screws 7 which may be conveniently formed in the top 8. Below 25 the rods 6 are the rods 9 which also extend transversely of the loom and have their opposite ends supported in the side plates 5 as indicated in Fig. 1. The rods 6 and 9 afford 30 guiding means for the drop wires, and while they are herein shown as circular in cross section, it is obvious they may be otherwise arranged. The drop wires 10 are provided 35 with openings 11 through which the guides 6 extend, Fig. 1. The lower portion of the drop wires 10 have the open slots 12 through 40 which pass the warp threads *a*. The warp threads *a* pass over the lower guide rods 9 and when they are in normal weaving condition, they support the weight of the drop wires, preferably one warp thread passing through each drop wire.

Each drop wire is provided with a laterally offset finger 13 which extends downwardly, and as will later appear, embraces 45 a portion of the detector when any one of the drop wires of either row fails to be supported by a warp thread. The offset relation of the fingers 13 with respect to the main body of the drop wires provides a 50 space 14 into which is received a portion of the detector when a drop wire is released by its warp thread. The detector is positioned between the two rows of drop wires. In the 55 present instance it is formed as a tube 15 having an open slot 16 extending longitudinally from one to the other side of the loom, as indicated in Fig. 1.

The detector is mounted for rocking movement in the side plates 5 and is supported 60 by bearings 17, one of which is indicated in Fig. 1, and detecting movement is imparted to the detector by a train of mechanism which in the present instance imparts to the detector an oscillating or rocking movement. Secured to the detector at one por-

tion thereof is the collar 18, Fig. 1. A set screw 19 affords a means for adjustably securing the collar 18 to the detector. Extending from the collar 18 is the arm 20 to which is connected the link 21, the other end of 70 the link being connected at 22 with a rocking lever 23 pivoted at 24 in one of the side plates 3, Fig. 1. The rocking lever 23 is extended downwardly at 25 and is connected at its lower end to the end of the link 26, 75 the other end of said link being connected at 27 to a lower arm 28 mounted on the rock shaft 29. The rock shaft 29 is appropriately supported as by the bearings 30 in the side plates 5, the construction being such that 80 rocking movement being imparted to the rock shaft 29, will transmit through the train of mechanism described, a rocking or oscillating movement to the detector 15. To the rock shaft 29 is connected a train of 85 mechanism of usual construction now well known in the art, for effecting loom stoppage when the rocking movement of the rock shaft is arrested as by the arrest of the detector by a drop wire. 90

The detector 15, which as hereinbefore stated, is positioned between two rows of drop wires, has two drop wire engaging portions 31 and 32 formed, in the present instance, by the upper slot or opening 16. 95 When the warp threads are in normal weaving condition as indicated in Fig. 1, the warp threads *a* support the drop wires with the laterally offset fingers above the slot 16 of the detector and the detector is permitted to 100 partake of its detecting movement.

When, however, a warp thread breaks or becomes too slack, the associated drop wire is permitted to drop as indicated in Fig. 2, whereupon a portion of the detector, (the edge 31 as indicated in Fig. 2) is embraced between the offset finger 13 and the main body of the drop wire, and before the detector is brought to rest by the released drop wire, the drop wire itself is distorted or 110 bent as indicated in Figs. 2 and 3, thereby causing the adjacent drop wires in the same row with the released drop wire to be separated laterally as indicated in Fig. 3, which at once makes apparent to the loom attendant or weaver the location of the faulty warp thread. 115

It will be noted that when a drop wire of either row is released by its warp thread, the offset finger 13 will drop into the slot or recess in the top portion of the detector and the detector, as it moves away from the row of drop wires in which the released drop wire is situated, exerts a bending force upon the drop wire between the upper and lower 120 guides 6 and 9 as indicated in Fig. 2; and since the main body of the drop wire rests against the exterior surface of the detector, the bending action is emphasized in turning the drop wire substantially into the position 125 130

shown in Fig. 3, which effects a separation of the adjacent drop wires of the same row, with the result that the weaver's attention is at once directed to the position of the 5 faulty warp thread.

The main body portion of the drop wires in the zone of action of the detector, are 10 preferably narrowed or made more flexible so that the bending action to effect the separation of drop wires of a row is facilitated without injury to the drop wires themselves.

What is claimed is:

1. In a warp stop motion for looms, the 15 combination of a plurality of drop wires arranged in parallel rows and normally supported by the warp thread during weaving, a detector positioned between the rows of drop wires and coöperating with the drop wires of either row and having a detecting 20 movement, each of the said drop wires being provided with a detector embracing portion which embraces the detector and arrests its detecting movement when a drop wire of either row fails to be supported by a warp 25 thread.

2. In a warp stop motion for looms, the 30 combination of a plurality of drop wires arranged in rows and normally supported by the warp threads during weaving, a detector positioned between adjacent rows of drop 35 wires to coöperate with the drop wires of either row and having a detecting movement wholly between the rows of drop wires, each of the drop wires being provided with a projecting finger extending downwardly to engage and arrest the detector when a drop wire fails to be supported by a warp thread.

3. In a warp stop motion for looms, the 40 combination of a plurality of drop wires arranged in parallel rows, a detector positioned between adjacent rows of drop wires to coöperate with the drop wires of either row and having a detecting movement wholly between the rows, the drop wires of adjacent 45 rows having at their adjacent edges detector-embracing portions which are normally held out of engagement with the detector by normal warp threads during weaving and which are constructed and arranged to embrace a 50 portion of the detector and arrest its detecting movement when any drop wire fails to be supported by a warp thread.

4. In a warp stop motion for looms, the 55 combination of a plurality of drop wires arranged in parallel rows and having downwardly extending detector engaging fingers on the adjacent edges of the drop wires of the two rows, a detector supported for detecting movement between two adjacent 60 rows of drop wires to coöperate with the drop wires of either row, two drop wire engaging portions on the detector, one for engaging a dropped wire of one row and the other for engaging a dropped wire of the 65 adjacent row for arresting movement of the

detector when a drop wire of either row fails to be supported by its warp thread and effecting a bend in the drop wire to separate it from adjacent drop wires in the same row.

5. In a warp stop motion for looms, the 70 combination of a plurality of drop wires arranged in two rows and each having an offset finger, guides for directing the movement of a drop wire, and a detector positioned between the two rows of drop wires and adapted to engage the offset finger of a drop 75 wire of either row when it fails to be supported by a warp thread and to bend the drop wire and indicate the position of the defective warp thread.

6. In a warp stop motion for looms, the 80 combination of a plurality of drop wires arranged in two rows and the drop wires of each row having flexing projections on their edges adjacent the opposite row, a detector 85 positioned between the two rows of drop wires and having two detecting edges, one for coöperating with the flexing fingers of one row of drop wires and the other for coöperating with the flexing fingers of the 90 other row to flex or bend a drop wire in either row and indicate the location of the deflector warp thread when a drop wire fails to be supported by its warp thread.

7. In a warp stop motion for looms, the 95 combination of a plurality of drop wires arranged in two rows, a detector positioned between the two rows of drop wires and having two detecting edges, each of the drop 100 wires in one row having a downwardly-extending finger laterally separated from the body of the drop wire toward the opposite row to straddle one of the detecting edges of the detector when the drop wire fails to be supported by its warp thread and effect 105 separation of the drop wires of the same row to indicate the location of the defective warp thread.

8. In a warp stop motion for looms, the 110 combination of a plurality of drop wires arranged in two rows and each having a downwardly-extending finger which is offset from the body of the drop wire toward the adjacent row, a guide for the drop wires, a detector positioned between the drop wires of adjacent rows and having a slotted portion 115 extending longitudinally thereof into which the downwardly-extending finger of a drop wire of either row extends when the drop wire fails to be supported by a warp thread, 120 and means for oscillating the detector to effect a bend in the drop wire before the movement of said means is arrested by the finger of the drop wire.

9. In a warp stop motion for looms, the 125 combination of a plurality of drop wires arranged in two rows and each having a downwardly-extending finger which is offset from the body of the drop wire toward the adjacent row, a guide for the drop wires, a de- 130

tector positioned between the drop wires of adjacent rows and having a slotted portion extending longitudinally thereof into which the downwardly extending finger of a drop wire of either row extends when the drop wire fails to be supported by a warp thread, and means for causing the detector to exert

a lateral pull upon the finger of the drop wire and effect a bend in the drop wire between the detector and drop wire guide to 10 separate the drop wires of the row.

In testimony whereof I have signed my name to this specification.

EUGENE L. TINKHAM.
